CLAIM

The ornamental design for a rechargeable battery, as shown
and described.

DESCRIPTION

FIG. 1 is a front, top, left perspective view of a first
embodiment of a rechargeable battery showing our new
design;

FIG. 2 is a rear, bottom, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a front, top, left perspective view of a second
embodiment of a rechargeable battery showing our new
design;

FIG. 10 is a rear, top, right perspective view thereof;

FIG. 11 is a rear, bottom, right perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof; and

FIG. 17 is a bottom plan view thereof.

The broken lines illustrating portions of the rechargeable
battery form no part of the claimed design.

1 Claim, 16 Drawing Sheets
